HYDRAULIC LIFT MECHANISM

Edward R. Barrett, Detroit, Mich., assignor to
 Gar Wood Industries, Inc., Detroit, Mich., a corporation of Michigan

Application March 30, 1938, Serial No. 198,974

4 Claims. (Cl. 298—22)

The present invention relates to vehicle body lifting mechanisms, and in particular provides an improved hydraulic mechanism for effecting a lifting or dumping movement of a vehicle body relative to its supporting frame.

Objects of the present invention are to provide an improved lifting mechanism characterized broadly in that it may be manufactured as a separate unit and installed upon existing vehicle frames without alteration in the construction or form thereof; to provide such a construction embodying supporting members adapted to be secured to a vehicle frame, and embodying hydraulically actuated ram mechanism disposed for connection to the vehicle body and actuatable to effect a tilting or dumping movement of the body; to provide such a construction embodying one or more fluid pressure actuated rams, disposed to be rigidly connected to a cross member, which cross member is disposed to be rotatably secured to the vehicle frame; to provide such a construction characterized in that the fluid for actuating the ram mechanism is disposed to be supplied through the supporting member; to provide such a construction arranged to support one or more ram mechanisms between the vehicle side frame members; to provide such a construction in which the cross member is disposed to support one or more ram mechanisms in outboard relation to the vehicle side frame members; to provide an arrangement of the last mentioned type including bearing supports for the outer sides of the outboard ram mechanisms; and to provide arrangements of the above generally indicated character which are economical of manufacture, simple of assembly, and which are extremely effective and serviceable in operation.

With the above, as well as other objects in view, which appear in the following description and in the appended claims, preferred but illustrative embodiments of the invention are shown in the accompanying drawings, throughout the several views of which corresponding reference characters are used to designate corresponding parts, and in which:

Figure 1 is a view in elevation of an illustrative dump type body construction with which the invention may be associated;

Fig. 2 is a view in elevation, with certain of the parts shown in section, of an illustrative embodiment of the invention;

Fig. 3 is a view in horizontal section, taken along the line 3—3 of Fig. 2;

Fig. 4 is a view in elevation of a modified struc-

ture, being the particular structure embodied in the arrangement in Fig. 1;

Fig. 5 is a view of another modification of the invention; and

Fig. 6 is a view of a further modification of the invention.

Referring first to the general view, Fig. 1, it will be appreciated that the illustrative vehicle body 10 is pivotally connected, by a suitable pivotal mounting 12, to the main frame 14 of the associated vehicle. The frame 14 is provided with the usual rear wheels, such as 15, and it will be understood that the front end 14a of the frame 14 may be connected to a suitable power unit in any usual way.

The mechanism to which the present invention particularly relates is designated as a whole in Figure 1 as 16, and comprises fluid pressure operated mechanism, which is pivotally connected, as indicated at 18, to the body frame 20, and is pivotally connected to the vehicle frame 14 by means of the hereinafter described sub-frame structure. When the ram 16 is in its retracted position, shown in Fig. 1, the forward end of the body frame 20 rests upon and is supported by the frame 14 of the vehicle. It will be appreciated that if the ram 16 is projected, it pivots the body 10 about the bearing 12 relative to the frame 14.

Referring particularly to Figs. 2 and 3, the lifting mechanism comprises a pair of similar, laterally spaced rams, 24 and 26. Each of the rams 24 and 26 preferably embodies the construction specifically described and claimed in applicant's copending application, Serial No. 199,485, filed April 1, 1938, and assigned to the same assignee as the present application. As described in more detail in the just identified copending application, the rams 24 and 26 are of the so-called displacement or telescopic type, and comprise a series of telescopically related cylindrical elements 28, 30, 32, and 34. The lower end of the outer cylindrical element 28 is closed by a plate 36, and the upper end of the inner cylindrical element 28 is closed by the member 38, which is formed to provide an eye 40 by which the ram may be connected to the body frame 20 by the previously mentioned pivotal connection 18.

The rams are preferably provided with cylindrical enclosing brackets 42, each having a tubular opening 44 therethrough which receives the associated ram, and also having an outwardly projecting flange 46 at one side and an outwardly projecting flange 48 at the other side.

Preferably, and as illustrated, each ram is secured within its associated bracket by forming a weld around the upper and lower end of each bracket.

5 The two flanged portions 46 of the rams 24 and 26 are rigidly secured to each other as by studs 52, and, as illustrated, it is preferred to interpose a gasket 54 therebetween. The outer flanges 48 associated with the two rams 24 and 10 26 are of tubular form and constitute bearings by which the ram mechanism is rotatably supported upon the sub-frame members designated as a whole as 60 and 61. The flange 48 associated with the right hand ram 26 rotatably receives a trunnion 62, the outer flange 64 whereof is secured as by bolts 66, to the web 68 of the sub-frame member 60. The flange 48 associated with the ram 24 rotatably receives a sleeve 70, which is non-rotatably connected to the web 72 15 of the sub-frame member 61 by bolts 74.

20 The sub-frame member 60 comprises a right angled member 76, having the previously mentioned web 68, to the back of which members 78, 80, and 82 are welded, or otherwise suitably secured, to constitute a box section. The members 78 and 80 have openings therethrough to accommodate the previously mentioned trunnion 62. The sub-frame member 60 rests directly upon one side of the main vehicle frame 14, with the box 25 section element 82 resting upon the flange 14b, and the web 68 lying in abutting relation to the web 14c of the frame. The web 68 is provided with a lug 84 to form a support for a bolt member 86, the hooked end 88 whereof hooks over the lower flange 14d of the frame. The box section 30 element 82 is provided with a downwardly turned flange 90 which hooks over the upper frame flange 14b. With this relation, it will be appreciated that by tightening down on the nut 92 associated with the bolt 86, the sub-frame member 60 is rigidly secured to the vehicle frame 14. The described arrangement is extremely advantageous in that it may be applied to existing frame constructions without requiring alterations 35 thereof in any respect and without requiring drilling of any mounting holes therethrough. The left hand sub-frame 61 corresponds in all respects to the arrangement just described with reference to the right hand sub-frame member 40 60.

50 The fluid for actuating the rams 24 and 26 is preferably introduced through a line 100, which may be connected to a suitable source of supply (not shown). The line 100 is rotatably connected 55 through a conventional union 102 to a short length of pipe 104 which passes axially through the previously mentioned sleeve 70, and is threaded into the bore of the flange 48 associated with the left hand ram 24. The pipe 104 thus pivots 60 as a unit with the ram 24. The pipe 104 opens into a circumferentially extending recess 106, provided in the bracket associated with the ram 24, and this recess opens directly into the bore 108 of said bracket. The just mentioned bore 65 108 communicates directly with the bore 110 of the companion bracket.

70 As clearly appears in connection with ram 24, the wall of the outer cylindrical element 28 thereof is provided with one or more openings, such as 112, which open into the space between the cylindrical elements 28 and 30. The ram 26 is, of course, correspondingly arranged so that the line 100 thus directly communicates with the interior of each ram.

75 As clearly appears in Figs. 2 and 3, the collar

114, which projects outwardly from the base of the cylinder 30 of each ram, and which forms a bearing connection between such cylinder and the outer cylinder 28, is provided with a number of grooves, such as 116. These grooves form a 5 fluid connection between the openings 112 and the chamber space 118 immediately above the base plate 36 of the associated ram.

10 With this arrangement, it will be appreciated that fluid supplied to the line 100 is free to circulate through the pipe 104, around the recess 106, and through the openings 112 into the ram 24. At the same time, the fluid is enabled to flow through the bores 108 and 110 into the ram 26 in corresponding manner. The fluid thus supplied is effective, as is described in more detail in the above identified copending application, to cause sequential projecting movements of the cylindrical elements 34, 32, and 30 relative to the outer cylindrical element 28. These projecting 15 movements cause a lifting of the vehicle body 10, during which lifting movement some pivotal action occurs between the body 10 and the ram structure 16, about the upper bearing 18. A corresponding pivotal movement occurs between the 20 rams 24 and 26 and the sub-frame members 60 and 61, during which movement the brackets 42 rotate relative to the trunnion 62 and the sleeve 70. During the latter pivotal movement, the connecting pipe 104 rotates with the rams 24 and 30 25 30 35 40 45 50 55 60 65 70 75 80 85 90 95 100 105 110 115 120 125 130 135 140 145 150 155 160 165 170 175 9945 9950 9955 9960 9965 9970 9975 9980 9985 9990 9995 9995 9995 9995 9995 9995

the outer ends of the transverse shaft member 138.

The transverse shaft member 138 is provided with a tubular bore 160 which extends entirely therethrough, and communicates adjacent its center with a passage 162 formed in a connecting member 164 which is rotatable relative to the transverse shaft member 138. The outer ends of the bore 160 communicate with corresponding bores 166 and 168 formed in the brackets 140 and 142, and these latter passages in turn communicate with the interiors of the rams 24' and 26' in the manner previously described with reference to the embodiment of Figs. 1 and 2.

With this relation, it will be appreciated that fluid may be introduced into and exhausted from the rams 24' and 26' through the transverse shaft member 138 and the connecting member 164. The rams 24' and 26' are rigidly secured to and so rotate with the shaft 138, thus eliminating the necessity of any fluid tight rotatable connection between the rams and the shaft. The provision of the single rotatable connecting member 164 makes it possible to connect the passage 162 with a rigid supply line, thus eliminating the necessity of flexible fluid connections for the hoisting mechanism.

The sub-frame members 134 and 136 constitute bearings which rotatably receive the transverse shaft member 138. Referring to the right hand side of Fig. 4, the sub-frame member 136 is provided with downwardly projecting bracket portion 170 which abuts the outer face of the main vehicle frame 132, and is also provided with a boss 175 which is provided with an opening to receive the shank of a hook shaped connecting bolt 172. The hooked end 174 of the bolt 172 engages below and behind the under side of the frame member 132, and a hooked portion 176, formed on the sub-frame member 136, correspondingly engages over the top of the vehicle frame. With this relation, it will be appreciated that by tightening down the nut, above boss 175 associated with the bolt 172, the sub-frame member 136 is drawn into and maintained in permanent fixed relation to the main vehicle frame member. The arrangement for the sub-frame member 134 duplicates the just described arrangement.

It will be appreciated that the operation of the embodiment illustrated in Fig. 4 duplicates the operation previously described, with the exception that the forces applied between the main vehicle frame and the main vehicle body are applied at points external to or in outboard relation to the main vehicle frame.

Fig. 5 discloses an embodiment of the invention embodying the features described above with reference to Fig. 4, and, in addition, embodying an additional outboard bearing for each ram. With this arrangement, each of the rams are disposed in outboard relation to the vehicle frame, and are provided with inner and outer bearings. In Figure 5, the brackets 180, which support the ram 24'', correspond in construction to the previously described bracket 140, with the exception that the bracket 180 is provided on its outer face with a trunnion 182, which is adapted to be rotatably received in a bearing provided therefor in an arm 184 which may be and preferably is formed at the end of a lateral extension 186 carried by the sub-frame member 188.

The remaining figure, No. 6, discloses an embodiment having the same general characteristics of Fig. 4, but utilizing a different form of support

bracket. In Figure 6, the bracket 190 associated with the ram 24''' includes a flange 192, for connection to the flange 194 of the associated transverse shaft member, and in addition, includes a substantially semi-circular grooved outer portion 196, within which the body of the ram 24''' is secured as by welding at a plurality of points such as 198.

It will be appreciated that the embodiments of Figs. 5 and 6 include companion and similarly constructed and arranged ram mechanisms at the opposite or right hand side of the associated vehicle, and that the operation of these embodiments corresponds in all respects to the operation of the embodiment of Figure 4.

It will also be appreciated that each of the herein described constructions may be readily and economically manufactured and may be correspondingly readily and economically installed upon the associated vehicle. In each instance, the ram mechanisms are assembled in unit relation with the main supporting members which extend between the two side members of the main vehicle frame, and these main supporting members are in turn secured to the frame in rotatable relation thereto by sub-frame members which are clampingly secured to the main frame. The entire hoisting mechanism may in each instance, therefore, be rapidly secured to and disconnected from the vehicle frame, the connecting operation being accomplished without the necessity of drilling or otherwise altering the form or shape of the vehicle frame in any respect.

Although specific embodiments of the invention have been described in detail, it will be appreciated that various modifications in the form, number, and arrangement of parts may be made therein without departing from the spirit and scope of the invention.

What is claimed is:

1. In a vehicle body hoisting mechanism in which said body is mounted on a frame, the combination with a pair of fluid pressure operated rams each having an outer cylinder provided with an aperture in the wall thereof, means connecting said rams to the vehicle body, a hollow bracket for each ram slideable over and rigidly secured to the cylinders between the ends thereof, said brackets each having a hollow boss communicating with said apertures, means rigidly connecting said bosses together providing communication between said rams, and means for supporting said brackets for pivotal movement upon the vehicle frame.

2. In a vehicle body hoisting mechanism in which said body is mounted on a frame, the combination with a pair of fluid pressure operated rams each having an outer cylinder provided with an aperture in the wall thereof, means connecting said rams to the vehicle body, a hollow bracket for each ram slideable over and rigidly secured to the cylinders between the ends thereof, said brackets each having a hollow boss communicating with said apertures, means rigidly connecting said bosses together, and means for supporting said brackets for pivotal movement upon the vehicle frame, said last named means including a hollow boss formed on each bracket, and a hollow trunnion member for each of said last named bosses disposed within such bosses, respectively, and connected to said frame.

3. In a vehicle body hoisting mechanism in which said body is mounted on a frame, the combination with a pair of fluid pressure operated rams each having an outer cylinder provided

- with an aperture in the wall thereof, means connecting said rams to the vehicle body, a hollow bracket for each ram slidable over and rigidly secured to the cylinders between the ends thereof, said brackets each having a hollow boss communicating with said apertures, said bosses being disposed in facing relationship with respect to each other, means rigidly connecting said bosses together providing communication between said rams, means for supporting said brackets for pivotal movement on the frame, said last named means including an outwardly disposed hollow boss formed on each bracket, and a hollow trunnion member for each of said last named bosses disposed within such bosses, respectively, and connected to said frame.
4. In a vehicle body hoisting mechanism in which said body is mounted on a frame, the combination with a pair of fluid pressure operated rams each having an outer cylinder pro-

vided with an aperture in the wall thereof, means connecting said rams to the vehicle body, a hollow bracket for each ram slidable over and rigidly secured to the cylinders between the ends thereof, said brackets each having a hollow boss 5 communicating with said apertures, said bosses being disposed in facing relationship with respect to each other, means rigidly connecting said bosses together providing communication between said rams, means for supporting said 10 brackets for pivotal movement on the frame, said last named means including an outwardly disposed hollow boss formed on each bracket, a hollow trunnion member for each of said last named bosses disposed within such bosses, re- 15 spectively, and connected to said frame, and means forming a fluid pressure passageway through one of said hollow trunnion members.

EDWARD R. BARRETT. 20
